UNITED STATES PATENT OFFICE.

JOHN MAXWELL COOTE, OF ELIZABETH, NEW JERSEY.

ELEVATOR SAFETY-CONTACT.

1,353,148.

Specification of Letters Patent. Patented Sept. 21, 1920.

Application filed December 24, 1918. Serial No. 268,190.

To all whom it may concern:

Be it known that I, JOHN MAXWELL Coote, a citizen of the United States, and a resident of Elizabeth, in the county of Union and State of New Jersey, have invented certain new and useful Improvements in Elevator Safety-Contacts, of which the following is a specification.

The invention relates to safety appliances as used in connection with electrically operated or electrically controlled elevators, lifts and the like where a door or gate is provided to prevent a passenger from leaving or entering the car; and more particularly to means for positively insuring, by mechanical means, the breaking of the actuating current circuit. In accordance with the present invention, this is effected through the operation of the said door or gate, or rather the unlocking instrumentality thereof, such as the well-known spring controlled hand rod.

In the accompanying drawings, which illustrate the invention—

Figure 1 is a fragmentary elevation showing the respective members in their proper relationship when the door is locked.

Fig. 2 is a fragmentary end view.

Similar characters of reference designate corresponding parts throughout the several views.

Referring to the drawings, 10 designates a suitable casing adapted to be secured to a wall or floor 11 surrounding the elevator shaft (not shown) and contains contact mechanism—for example, of the character set forth in a prior Patent No. 1,277,868, granted to me the 3rd day of September, 1918. In the contact mechanism aforesaid, 40 the contact is broken under the action of resilient means and through gravity. While these same forces are employed in the present device, the action is further positively insured by mechanical means which will 45 doubly safeguard the operation of the elevator. The contact mechanism referred to may consist of a contact block 12 providing a curved surface 13 opposite the free end 14 of a spring member 15 secured at one end to the 50 casing 10. To the spring is also attached an inward extension 16 of an arm 17 movably secured to the casing. The arm carries, also, a link 18 which is projected outwardly through a slot 19 of the casing 10 substantially in the axis of the arm 17. Beyond the 55 casing 10, link 18 is provided with a pin 20

projecting perpendicularly therefrom into a slot 21 of the weighted arm 22 of a lever pivoted to the wall 11. The other arm of this lever is provided with a latch 23 adapted 60 to engage with a catch 24 secured to a plate 30 which, in turn, is carried by the door 25. The plate 30 carries, also, a lever whose inner end 31 extends beyond and behind the spring-urged hand rod 32 of well-known construction and designed to unlock the gate. For this purpose, the said rod 32 carries a pin 33 projecting perpendicularly therefrom backwardly over the arm 31 and is designed to engage with its upper surface to depress 70 the arm to the dotted position indicated, when the said rod 32 is drawn downwardly to release the gate. The other arm of the lever is provided with a nose 34 which, when the said rod 32 is drawn downwardly, as 75 aforesaid, engages the under-surface 35 of the latch 23 to throw same upwardly to the position indicated in dotted lines, and correspondingly depresses, to the position indicated in dotted lines, the arm 22. This latter 80 arm, through the pin and slot connection 20 and 21, will draw link 18 outwardly to break the contact at the surface 13 and end 14, and thus prevent the operation of the elevator so long as the gate is unlocked or 85 open. Arm 22, being constructed relatively heavy, gravity will also assist in effecting this break in the circuit, but the same is positively insured through the operation of the nose 34 against the latch 23, the motion of 90 which nose serves, also, to release the latch 23 from its catch 24 and thus permit the door to be opened by moving in the direction indicated by the arrow.

To restore the contact, and render the 95 current available for operation of the elevator driving mechanism (not shown), the upper end 36 of rod 32 is arranged to bear against the lower surface 37 of the arm 22, and thus positively force the same upwardly to 100 the position indicated in full lines. This restores, also, the locking engagement between latch 23 and catch 24 to lock the said gate, the pin 33, moving upwardly with the rod to permit of the return of nose 34 to its 105 normal position.

It will be apparent, therefore, that so long as the gate is not properly closed or locked, the electrical contact will be broken between the surface 13 and end 14, and no current 110 can be supplied to the elevator driving mechanism, obviating any danger from premature

starting of same. As soon, however, as the door is properly closed, thus barring any entry or exit to or from the elevator, the contact has been positively restored, and the 5 operating current is available.

I claim:

1. In a safety appliance for electrically controlled elevators and the like: a gate, a catch carried by the gate, a contact-making member, a releasing instrumentality, a pivoted latch member, one arm of same being designed to engage the said catch and the other arm connected with said contact-making member, a disengaging lever pivotally carried by the gate, adapted to engage with said latch member to free the latch from the catch, and having an arm actuated from said releasing instrumentality whereby when the same is drawn in one direction, the disengaging lever is actuated, said releasing instrumentality being adapted to engage the contact operating arm of the latch member in the other direction of its movement to restore the locking engagement and to effect 20 a closure of the contact by the contact-making member.

2. In a safety appliance for electrically controlled elevators and the like: a gate, a catch carried by the gate, a contact-making member, a hand rod for releasing the elevator gate, a pivoted latch member, one arm of same being designed to engage the said catch and the other arm connected with said contact-making member, a disengaging 30 lever pivotally carried by the gate, adapted to engage with said latch member to free the latch from the catch, and having an arm engaged by a pin projecting from said hand rod whereby when the same is drawn in one direction, the disengaging lever is actuated, said rod being adapted to engage the contact operating arm of the latch member in the other direction of its movement to restore the locking engagement and to effect 40 a closure of the contact by the contact-making member.

3. In a safety appliance for electrically controlled elevators and the like: a gate, a catch carried by the gate, a contact-making member, a hand rod for releasing the elevator gate, a pivoted latch member, one arm of same being designed to engage the said catch and the other arm overbalancing said latch portion and connected with said contact-making member, a disengaging lever 50 pivotally carried by the gate, adapted to engage with said latch member to free the latch from the catch, and having an arm engaged by a pin projecting from said hand rod whereby when the same is drawn in one direction, the disengaging lever is actuated, said rod being adapted to engage the contact operating arm of the latch member in the other direction of its movement to restore the locking engagement and to effect a closure 60 of the contact by the contact-making member.

4. In a safety appliance for electrically controlled elevators and the like: a gate, a catch carried by the gate, a movable contact-making member, a hand rod for releasing the elevator gate, a pivoted latch member, one arm of same being designed to engage the said catch, a link connecting the other arm thereof to the contact-making 70 member, a disengaging lever pivotally carried by the gate, adapted to engage with said latch member to free the latch from the catch, and having an arm engaged by a pin projecting from said hand rod whereby when the same is drawn in one direction, the disengaging lever is actuated, said rod being adapted to contact with one side of the link arm of said latch member in the other direction of its movement to restore 75 the locking engagement and to effect a closure 80 of the contact by the contact-making member.

Signed at New York, in the county of New York and State of New York, this 23rd 90 day of December, A. D. 1918.

JOHN MAXWELL COOTE.
